Primary Examiner — Elizabeth J Oswecki(74) Attorney, Agent, or Firm — Tutunjian & Bitetto, P.C.(57) CLAIM

The ornamental design for a peeler, as shown and described.

DESCRIPTION

FIG. 1 is a perspective view of a peeler showing my new design;

FIG. 2 is a front view thereof;

FIG. 3 is a back view thereof;

FIG. 4 is a left side view thereof;

FIG. 5 is top view thereof;

FIG. 6 is a right side view thereof; and,

FIG. 7 is a bottom view thereof.

The broken lines shown in FIGS. 1-7 represent unclaimed portions of the peeler and form no part of the claimed design.
